UNITED STATES PATENT OFFICE

ARTHUR H. BERNTSON AND CLIFFORD J. ZIMMERMAN, OF SALT LAKE CITY, UTAH

EAR TAG

Application filed October 9, 1929. Serial No. 398,303.

This invention relates to an ear tag and particularly an ear tag used for identifying animals, such as ordinary livestock. The principal objects of the invention are:

5 First. To provide a tag which shall be simple and easily applied.

Second. A tag whose fastening members shall be particularly strong and durable.

10 Third. A tag in which protruding parts shall, as far as possible, be eliminated.

Ear tags are usually made of strips of metal, such as aluminum, bent partly around the ears, and provided with pointed tongues at one end for piercing the ears, the tongues 15 being finally clinched after passing through an opening in the other end of the bent strips.

Certain features of the present invention are similar to features represented in the ear 20 tag forming the subject of U. S. Patent 1,510,083, granted Sept. 30, 1924, to A. H. Berntson, while certain other features constitute a decided improvement over the said earlier tag.

25 A distinguishing feature of the present invention is that the point or tongue having a buttressed rib, is bent outwardly in relation to the body of the tag, instead of inwardly, in the process of fastening the tag. 30 Due to this construction, we are enabled to extend the reinforcing rib very close to the tip of the tongue, so that the rib is useful not only during the operation of clinching the tag, but afterwards serves to greatly 35 strengthen the bend of the clinched tongue. Also due to the fact that the tongue is bent outwardly instead of inwardly, its manipulation in clinching takes place in a more accessible and convenient place, making possible the formation of a much more perfect 40 fastening than heretofore.

The features of this invention for which the protection of Letters Patent of the 45 United States is desired, are collectively grouped in the claims concluding this specification.

In the drawings,

Fig. 1 represents a plan of the tag in its 50 developed or unbent form, viewing the sur-

face which becomes the outside of the finished tag;

Fig. 2, a side elevation of the tag ready to be applied;

Fig. 3, a side elevation, partly in section 55 and drawn to an enlarged scale, in its final form when clasped in the ear of an animal;

Fig. 4, a top plan view corresponding to Fig. 2; and

Fig. 5, a section on line 5—5, Fig. 2, parts 60 in the background being omitted.

Referring to the drawings, the tag in its preliminary stage consists of a body strip 10 having its two extremities formed substantially as shown in Fig. 1. This strip is 65 initially bent into substantially the shape shown in Fig. 2, ready for insertion in the pliers or tongs, by the use of which the tag is attached to an ear.

In the initial shape, Fig. 2, as well as in 70 the finished shape, Fig. 3, a base portion 12 projects from the portion 10—1 of the body, the two being substantially at right angles to each other. The base forms a support 75 for the tongue and is reinforced by the rib 14, buttressed at 14—1 against the body portion 10—1.

In applying the tag to the ear of the animal, by means of the pliers (not shown), the tongue 15 is forced through the substance of the ear, and then passed through the opening 16 in the portion 10—2, this opening being located at the end of the body. As the tip of the tongue emerges from opening 16, it is turned outwardly, that is, to the left of the face plane indicated by the line $a-a$, 80 in Figs. 2 and 3, the base being considered as positioned on the inside of the plane $a-a$. The tongue may be finally bent around the bar 17, coming to rest in the recess 18 which is defined between the guards 19, and forming substantially a clinch curled around the bar.

It will be noticed particularly, that the 85 portion 14—2 of the rib, constitutes a reinforcement clear over and around the bend 20 of the tongue 15, as indicated in Fig. 3, thus strengthening the tongue greatly.

By bending the tongue away from the rib, 90 the latter in the process of forming, is 100

stretched, resulting, as is well known in engineering practice, in a better disposition of the metal, than would be the case should the tongue be bent inwardly or towards the 5 rib, which latter process would result in a compression or crumpling of the rib.

In the finally clinched position, the contour 21 across the clinched end of the tag, follows a smooth curve as shown in Fig. 4, 10 so that the guards 19 which are integral with bar 17 on both sides of the tongue, together with the bend 20, form substantially only a single protrusion from the finished 15 body, thus reducing the likelihood of disengaging the tag from such clinched position.

While a specific embodiment of our invention is herein shown and described, it is to be understood that various changes could be made therein, without departing from the 20 spirit and scope of the invention as defined in the claims.

Having fully described our invention, what we claim is:

1. An ear tag comprising in combination, 25 a body, a base portion extending from said body at one end thereof and positioned substantially on the inside of a face plane; means, including a bar, defining an opening at the opposite end of said body, a tongue projecting from said base portion through said opening, the said tongue having a clinch positioned on the outside of the face plane and guards on both sides of said tongue, the contour of the clinched tongue and guards forming a 35 smooth curve.

2. An ear tag comprising in combination, a body, a base portion extending from said body at one end thereof and positioned substantially on the inside of a face plane, means 40 defining an opening at the opposite end of said body, a clinch on said base portion, said clinch positioned just beyond said opening and on the outside of said face plane, and a buttressed rib projecting from said base, said 45 rib extending on the outside of, and substantially around, said clinch.

3. An ear tag, including in combination, a body portion having an opening therein, a base below said opening, a bent clinch projecting from said base through said opening, and a rib around the outside of the bend of 50 said clinch.

4. An ear tag, including in combination, a body portion having a bar at one end thereof, 55 a base adjacent said bar and positioned to the inside of said bar, a curled clinch projecting from said base around said bar, and a rib extending on the outside of, and substantially around, said curled clinch.

60 5. An ear tag, including in combination, a body portion having an opening therein, a bar adjacent said opening, guards spaced apart from each other adjacent said bar, a base below said opening, a curled clinch projecting from said base around said bar, said 65

curled clinch being positioned between said guards, and a rib extending on the outside of, and substantially around, said curled clinch.

6. An ear tag, including in combination, a 70 body portion having a base at one end thereof, a bar at the other end of said body portion, said bar located outside the outer face plane of said base, a curled clinch integral with said base, said curled clinch extending around said 75 bar, and a buttressed rib extending from the inside of said base to and around said curled clinch.

7. An ear tag comprising the combination 80 with a U-shaped body, of means defining an opening in one end of said body, a base at the other end of said body, said base being at substantially right angles to the said body and extending to said opening, a bar adjacent said opening and positioned to the outside of the 85 outer face plane of said base, a curled clinch extending from the said base around said bar, and a rib extending on the outside of, and substantially around, said curled clinch.

In testimony whereof we sign our names 90 hereto.

ARTHUR H. BERNSTON.
CLIFFORD J. ZIMMERMAN.
